NOYES JUSTIN SMITH, OF ATTLEBORO, MASSACHUSETTS, ASSIGNOR TO
G. A. DEAN COMPANY, OF SAME PLACE.

CHATELAINE-PIN.

SPECIFICATION forming part of Letters Patent No. 681,984, dated September 3, 1901.

Application filed June 14, 1901. Serial No. 64,539. (No model.)

To all whom it may concern:

Be it known that I, NOYES JUSTIN SMITH, a citizen of the United States, residing at Attleboro, in the county of Bristol and State 5 of Massachusetts, have invented a new and useful Improvement in Chatelaine-Pins, of which the following is a specification.

This invention has reference to an improvement in pins for supporting a series of articles connected to the pin.

The invention consists in the peculiar and novel construction whereby a watch and a series of articles may be connected with the pin.

Figure 1 is a front view of the improved 15 chatelaine-pin. Fig. 2 is a rear view of the same. Fig. 3 is a sectional view showing the spring-wound watch-chain. Fig. 4 is a transverse sectional view of the pin.

The object of the invention is to provide 20 the chatelaine-pin with an extensible watch-chain, so that a watch carried in the belt to which the chatelaine-pin is attached may be secured.

In the drawings, *a* indicates the face-plate; 25 *a'*, a circular recess or cavity in the back of the face-plate; *b*, a circular cap, the peripheral rim *b'* of which extends into the cavity *a'*; *c*, a perforated plate pivotally supported around the post *c'*, secured to the back of the 30 cap *b*; *d*, a ring on the plate *c*; *d'*, a spiral spring secured at one end to the post *c'* and at the other end to the ring *d*, and *e* a flexible chain secured at one end to the ring *d*, extending through the opening *b''* in the rim *b'* and 35 secured to the watch-chain swivel. The face-plate *a* extends beyond the peripheral rim of the cap *b*, and the cap extends rearward beyond the face-plate sufficient to permit the free movement of the watch-chain. To the 40 back of the cap *b* are secured the hinge *g*, on which the pin *g'* is secured, the hook *g''*, and

a number of loops *g³*, to which the pendants *g⁴* are secured.

To secure ready access to the interior for the adjustment of the spring or chain, the cap 45 *b* is provided with the lip *b³*, which enters an undercut in the cavity *a'* and with the snap edge *b⁴* enters a depression or hole in the spring-post *b⁵*.

The watch is secured to the chain-swivel *f*, 50 and when the chatelaine-pin is secured, as usual, to the belt the watch is securely held against loss by the watch-chain. When the watch is withdrawn for examination, the watch-chain is drawn out against the tension 55 of the coiled spring and is automatically drawn in by the rotation of the ring *d*, operated by the coiled spring.

Having thus described my invention, I claim as new and desire to secure by Letters 60 Patent—

In a chatelaine-pin, the combination with the face-plate *a*, having the cavity *a'* in the back of the face-plate, the cap *b* detachably secured to and projecting beyond the back of 65 the face-plate, the pin *g'* pivotally secured to the back of the cap *b*, a number of devices *g³*, and the pendants *g⁴ g⁴*, of the plate *c*, the fixed post *c'* on the back, the ring *d*, the coiled spring *d'* connected with the post *c'* 70 and the ring *d*, the watch-chain *e* secured at one end to the ring *d*, and the chain-swivel *f* secured to the other end of the watch-chain, as described.

In testimony whereof I have signed my 75 name to this specification in the presence of two subscribing witnesses.

N. JUSTIN SMITH.
